US00D669792S

(12) **United States Design Patent**
Lorenz(10) **Patent No.:** **US D669,792 S**
(45) **Date of Patent:** **** Oct. 30, 2012**

- (54) **SPRAY DISPENSING CONTAINER**
- (75) Inventor: **Mike Lorenz**, Gahanna, OH (US)
- (73) Assignee: **R.J. Reynolds Tobacco Company**, Winston-Salem, NC (US)
- (**) Term: **14 Years**
- (21) Appl. No.: **29/387,237**
- (22) Filed: **Mar. 10, 2011**
- (51) **LOC (9) Cl.** **09-01**
- (52) **U.S. Cl.** **D9/687; D9/686**
- (58) **Field of Classification Search** D9/682-694, D9/516-575, 434-455, 723-729; D28/5, D28/76, 77, 91.1; 222/129, 135, 153.01, 222/153.03, 153.04, 153.09, 153.11-153.14, 222/182, 631, 635, 209, 211-213, 215, 321.7-321.9, 222/372, 373, 378, 379, 383.1, 384-386, 222/398, 400.7, 400.8, 401, 402.1-402.25; D24/108, 110, 110.5; 128/200.12, 200.14, 128/200.17-200.23, 203.12-203.24; D27/139, D27/141-161, 172, 183-194

CN 3402102 11/2004

(Continued)

Primary Examiner — Catherine Tuttle(74) *Attorney, Agent, or Firm* — Womble Carlyle Sandridge & Rice, LLP(57) **CLAIM**

The ornamental design for a spray dispensing container, as shown and described.

DESCRIPTION

FIG. 1 is a bottom, right side and front perspective view of the spray dispensing container showing my new design;
 FIG. 2 is a right side elevational view thereof;
 FIG. 3 is a left side elevational view thereof;
 FIG. 4 is a rear elevational view thereof;
 FIG. 5 is a front elevational view thereof;
 FIG. 6 is a top plan view thereof;
 FIG. 7 is a bottom plan view thereof; and,
 FIG. 8 is a bottom, right side and front perspective view of the container shown in an open configuration.
